Robert Dougherty Inventor
By his Attorney
James Hamilton

UNITED STATES PATENT OFFICE.

ROBERT DOUGHERTY, OF NEW YORK, N. Y.

PLUMBER'S FITTING.

1,205,978.

Specification of Letters Patent. Patented Nov. 28, 1916.

Application filed September 18, 1916. Serial No. 120,610.

To all whom it may concern:

Be it known that I, ROBERT DOUGHERTY, a citizen of the United States of America, residing in the borough of the Bronx, city of New York, in the county of Bronx and State of New York, have invented certain new and useful Improvements in Plumbers' Fittings, of which the following is a specification, reference being had to the accompanying drawings.

This invention relates to improvements in plumbers' fittings; and an object of this invention is to provide a plumber's fitting which will be simple in construction, comparatively cheap in manufacture, and efficient and durable in operation and use.

Another object of this invention is to provide a plumber's fitting the labor involved in the installation of which will be greatly reduced as compared with plumbers' fittings heretofore in common use.

In the drawings illustrating the principle of this invention and the best mode now known to me of applying that principle, Figure 1 is an elevation of a stack of which my new fitting forms a part; Fig. 2 is a horizontal section on the line 2—2 of Fig. 1; Fig. 3 is a central, longitudinal, vertical section through a fitting adapted and arranged for the top of the stack; Fig. 4 is a section similar to Fig. 3 but through a fitting adapted and arranged for the bottom of the stack; Figs. 5, 6, 7 and 8 are sections on the lines 5—5, 6—6, 7—7 and 8—8, respectively, of Figs. 3 and 4; Fig. 9 is a central, longitudinal, vertical section through an intermediate fitting; and Figs. 10 and 11 are sections on the line 10—10 and 11—11, respectively, of Fig. 9.

The fitting *a* (Fig. 9) is made preferably in the form of a one-piece casting the space within the casing *a** of which is divided, by substantially upright partition-walls *b* into a series of substantially vertical depthwise-extending passages or channels *c*, *c'*, *c''*, *c'''* the upper ends of which communicate freely with the upper lateral or transverse air-passage *d*, and which empty or discharge into the lateral or transverse waste-water passage *e*. At one end or side of each intermediate fitting *a* (Fig. 9), there is an air pipe (or vent-pipe) section *f* which communicates, through an inner hole or opening *f'*, with one end of the lateral air-passage *d*; while, at the opposite end or side of the fitting *a*, there is a section *g* of the soil-pipe

or waste-pipe, which communicates through an inner hole or opening *g'* with the lateral or transverse waste-water or soil passage *e*. The front and back walls *h*, *h'*, of the casing *a** are formed with openings for the entrance of the waste into the fitting, there being, in the form illustrated, an inlet opening into each of the four depthwise-extending passages *c*, *c'*, *c''* and *c'''*. Into each of these openings, there is fitted a waste-pipe leading from one of the plumbing fixtures; thus, the front wall *h* is formed with an opening *i* in which is fitted the discharge end of the waste-pipe *j*' that leads from the sink *k* and set of washtubs *k'* (Fig. 2) to the depthwise-extending channel *c'*, while the other or back wall *h'* of the fitting is formed with the openings *i*, *i''*, *i'''*, in which are fitted, respectively, ends of the waste-pipes *j*, *j''*, *j'''*, that lead from the bath-tub *m*, the watercloset *n* and washstand *o*, respectively. These openings *i*, *i'*, *i''*, *i'''*, are so placed that each of the waste-pipes *j*, *j'*, *j''*, *j'''*, communicates with one of the passages *c*, *c'*, *c''*, *c'''''*; thus, the waste-pipe *j* leads from the bath-tub *m* and discharges the waste-water therefrom through the opening *i* into the passage *c*; the waste-pipe *j'* conducts the waste-water from the sink *k* and set of washtubs *k'* and empties, through the openings *i'*, into the passage *c'*; the waste-pipe *j''* leading from the water-closet *n* communicates with the passage *c''* through the opening *i''*; and the waste-pipe *j'''*, through which flows the water discharged by the washstand *o*, directs the water through the opening *i'''*. Of course, where one of the fixtures just named (e. g., the washstand *o*) is not installed, a narrower fitting with one less depthwise-extending passage may be used; while, where additional fixtures are used, there may be substituted for the fitting *a*, a wider fitting formed with extra passages with which the waste-pipes from the additional fixtures will communicate. The waste flowing through the passages *c*, *c'*, *c''*, *c'''''*, is discharged into the lower lateral passage *e* which is somewhat inclined toward the waste-water pipe or soil-pipe *g* and communicates therewith through the inner opening *g'*.

In Figs. 3, 5 and 6, there is illustrated, in sectional views, a fitting *a'* that is particularly adapted and arranged for use as the topmost fitting of the stack *A* (Fig. 1). In this form of fitting, the channel *f''*, which

- forms the upper section of the line of air-pipe, is closed at its top with the exception of the inner hole or opening i^* through which the air flows into the upper lateral 5 passage d and thence, through the inner opening g^* , into the section g'' of the line of soil-pipe or waste-pipe. A vent pipe g^* is connected with the section g'' and extends through the roof p (Fig. 1).
- 10 There is shown in the sectional views, Figs. 4, 7 and 8, a fitting a'' that is particularly adapted and arranged for use as the lowermost fitting of the stack A (Fig. 1). In this form of fitting, the inner wall of the 15 section f of the line of air-pipe, which section is illustrated in Fig. 9, is omitted, so that the depthwise-extending passage adjacent to the air-pipe section merges into the latter, whereby the passage c^* of Fig. 20 4 is wider than the corresponding passage c of Fig. 9. The opening i^* , which corresponds to the opening i of Fig. 9, is located, in the bottom fitting a'' , close to the air-pipe side or end thereof (Fig. 4). To 25 the lower end of the waste-pipe section g , there is connected the upper end of a section q of the drain-pipe. The fittings a'' , a' , a , are connected with one another by means 30 of the pieces r of the line of air-pipe or vent-pipe and by means of the pieces s of the line of waste-pipe or soil-pipe, thereby forming the stack A (Fig. 1).

It will be obvious to all persons skilled in this art that the plumber's fitting hereinbefore described complies with every requirement of the most advanced sanitary laws and requires for its installation much less labor and material than is needed to install any of the fittings heretofore in common 35 use. The fitting may be made of wrought or cast iron and is adapted for use in apartment houses, office buildings, dwelling houses, stores and buildings used for other purposes. The fittings a , a' , a'' may be connected to the pieces of piping r , s , by calked joints instead of using the screw-joints r' , s' shown.

I claim—

1. A plumber's fitting including a casing 50 formed near its top with a laterally-extending air-passage and near its bottom with a laterally-extending waste-water passage and between said passages with a series of depthwise-extending channels the upper ends of 55 which communicate with said air-passage and the lower ends of which communicate

with said waste-water passage; and a waste-pipe section arranged within said casing and formed with an opening through which said waste-water passage communicates with 60 said waste-pipe section; said casing being formed with inlet openings arranged to permit the entrance of waste into said channels from outside the fitting.

2. A plumber's fitting including a casing 65 formed near its top with a laterally-extending air-passage and near its bottom with a laterally-extending waste-water passage and between said passages with a series of depthwise-extending channels the upper ends of 70 which communicate with said air-passage and the lower ends of which communicate with said waste-water passage; a waste-pipe section arranged within said casing and formed with an opening through which said 75 waste-water passage communicates with said waste-pipe section; and an air-pipe section arranged within said casing and formed with an opening through which said air-passage communicates with said air-pipe 80 section; said casing being formed with inlet openings arranged to permit the entrance of waste into said channels from outside the fitting.

3. A plumber's fitting including a casing 85 formed near its top with a laterally-extending air-passage and near its bottom with a laterally-extending waste-water passage and between said passages with a series of depthwise-extending channels the upper ends of 90 which communicate with said air-passage and the lower ends of which communicate with said waste-water passage; a waste-pipe section arranged within said casing and formed with openings through which said 95 passages communicate with said waste-pipe section; and an air-pipe section arranged within said casing and formed with an opening through which said air-passage communicates with said air-pipe section; said 100 casing being formed with inlet openings arranged to permit the entrance of waste into said channels from outside the fitting.

Signed at the city of New York, county of Bronx and State of New York, this 15th 105 day of September, A. D. 1916, in the presence of the two undersigned witnesses.

ROBERT DOUGHERTY.

Witnesses:

JOHN J. GREEN,
J. J. COLEMAN.
